ALFRED LEE MOORSHEAD, OF ARLINGTON, NEW JERSEY.

FREIGHT-CAR-HEATING SYSTEM.

1,318,457.

Specification of Letters Patent. Patented Oct. 14, 1919.

Application filed August 1, 1914. Serial No. 854,535.

To all whom it may concern:

Be it known that I, ALFRED LEE MOORSHEAD, a citizen of the United States, and resident of Arlington, in the county of Hudson and State of New Jersey, have invented certain new and useful Improvements in Freight-Car-Heating Systems, of which the following is a specification.

My invention is designed for use in connection with chambers for the storage or transportation of such goods as should be kept at a different temperature from that of the outside atmosphere, for instance above the freezing point during freezing weather, and in certain of its features is particularly applicable to freight cars having insulated walls.

One important feature of my invention involves certain improvements in the construction, arrangement and placing of a radiator through which a heating medium may be circulated to raise the temperature of the interior of the car to the desired extent. The radiator may occupy such a position as not to interfere with the contents of the car, or reduce the capacity of the storage space when the car is used for the shipment of goods which do not require to be heated. One feature of my invention involves the mounting of the radiator whereby the latter may be brought out to such a position that the air may freely circulate about it, and a proper current of heated air delivered to the body of the car, or the main storage chamber thereof. Another important feature of my invention relates to the means for maintaining the interior of the car properly heated while the latter is being loaded from a ship, or when the car is being transported by water.

My improved system may be employed in connection with the transportation of any kind of goods which it is desired to maintain at a temperature above that of the outside air, and the temperature in the chamber of the car may be maintained as high or low as desired. For instance, in the transportation of green bananas and pineapples, it is very essential that the fruit be kept warm, as any approach toward the freezing point is not only detrimental, but delays the ripening process. In the transportation of such vegetables as potatoes, and turnips, or the like, a much lower temperature is per-

missible, although a freezing temperature is injurious.

Practically all of the bananas and pineapples arriving in this country come by ship and are unloaded from the ship directly into cars for transportation to inland points. By means of my invention, it is possible to take cold cars from the yard to the dock or pier, or to run the cold cars directly on to a car float and transmit them to the side of the ship, and have the cars properly heated by the time they arrive at the ship side ready to receive its cargo. The fruit may be taken directly from the warm hold of the ship and delivered into the warmed cars, without liability of injuring the fruit. The car may be kept heated while being returned to the railroad yard or terminal, while standing in the yard and while in transit along the road. The insulation wall will retain the heat while the cars are being transferred from the float to the tracks. Thus the fruit may be kept properly warmed from the time it is loaded on the ship until it is unloaded from the cars at the final point of disposal.

Various changes may be made in the construction and operation of apparatus designed for carrying out my invention, and I therefore desire the specific constructions shown in the accompanying drawings to be considered in an illustrative rather than in a limiting sense. In these drawings to which reference is to be had and upon which similar reference characters indicate corresponding parts in the several views:

Figure 1, is a longitudinal section through one end portion of a freight car constructed in accordance with my invention, said section being taken approximately on line 1—1 of Fig. 2.

Fig. 2, is a transverse section of the car taken on the line 2—2 of Fig. 1.

Fig. 3, is a top plan view of the radiator, and

Fig. 4, is a partial horizontal section through the car, and taken on the line 4—4 of Fig. 2.

I have illustrated my invention as applied to a type of freight car, having comparatively thick walls of insulated construction, such as is commonly employed in refrigerator cars. In fact my invention may be employed directly in a refrigerator car, so that

the car may be employed for the transportation of such freight as may require a temperature either below or above that of the outside atmosphere. The specific car illustrated in Figs. 1 to 5 inclusive has a floor or bottom wall 10, end walls 11, side walls 12, and a top wall or roof 13, each made up of a plurality of spaced layers leaving insulated air chambers therebetween. In one or both ends of the car, there is formed an ice chamber 14, separated from the main storage chamber of the car by a reticulated partition 15.

In applying my invention to such a car, I preferably form a recess in one of the walls, the particular one being preferably the bottom wall or floor 10, although I might form it in the side or end wall. The inner lining or layer of the wall and certain of the intermediate layers may be removed over certain limited areas, and a plurality of shallow recesses 16 thus formed. Within each recess, I mount a radiator 17, which is also preferably comparatively thin or shallow and which may be formed of pipes including a series of straight lengths and return bends. The radiator may be disposed entirely within the recess so that its upper surface will be below the inner surface of the car floor, but in certain constructions is so mounted that it may be raised out of the recess and held in such raised position. Although I have shown the radiator only in the floor and only in a recess, other arrangements within the scope of the appended claims might be employed. Preferably the supporting means for the radiator includes a plurality of links 18 and 19 each pivoted to the radiator and to the floor, so that the radiator may swing upwardly and endwise into parallelism, for instance from the position shown in solid lines of Fig. 1, to the position shown in dotted lines.

The radiator may be connected to a source of supply of heating medium in any suitable manner, but preferably two of the links 19 are in the form of pipes with swivel connections at the ends so that the supply of steam to the radiator and the escape of exhaust therefrom will not be affected by a raising or lowering of the radiator.

The swivel or pivotal joints may be of any well known type.

With the radiator in this lower or what may be termed inoperative position, the recess may be closed by a cover plate 20, so that the inside floor of the car will be substantially smooth and uninterrupted and the ordinary freight which it is not necessary to heat, may be wheeled or pushed across the floor, and the storage chamber of the car not diminished in any way by the radiator. This cover plate may be entirely independent of the radiator, and may be removable or hinged or it may be secured to or supported

on the radiator. In this case, the cover above the radiator when the latter is in raised position, would prevent the direct upward movement of heated air from the radiator and would insure a horizontal delivery of the heat and a better distribution throughout the car.

For supporting the goods or packages containing the same in the car, when the radiator is in raised position, I provide a false flooring 21 preferably constructed in sections, and each section being so formed as to permit the free circulation of air therethrough. Preferably this flooring is formed of a series of slats or narrow boards spaced a short distance apart, and secured to a series of supporting strips 20 which are also preferably perforated, and arranged so as to rest upon the solid portions of the floor between the radiators, when the flooring is in position and the radiators are raised as shown in Fig. 2. The supports hold the flooring at only a slight distance above the radiators, and permit currents of heated air from the radiators to pass both horizontally and vertically and so distributed throughout the body of the car.

When the radiator is in lowered position, that is concealed within its recess, I preferably remove the false flooring so as to thereby increase the storage capacity of the bottom of the car and facilitate the movement of freight thereacross. In order that the false flooring may be available at all times, I preferably provide the side walls 100 of the car with small brackets adjacent to the ceiling or roof of the car, so that the separate sections of the false flooring may be raised and fastened closely adjacent to the ceiling, as shown in Fig. 1. When the false flooring is in this position and the radiators are concealed within their respective recesses, the capacity of the car will not be materially reduced.

For delivering heating medium to the car, any suitable form of piping, preferably beneath the floor of the car, may be provided. As shown, the radiators are arranged in pairs and supply pipes 23 extend through the floor and connect to a main pipe 24 extending lengthwise of the car. The outlet from each radiator may discharge to a return pipe line or deliver directly to the outside atmosphere, but preferably an outlet pipe 25 extends through the floor of the car and has a condenser trap 26 controlled either by pressure or temperature of the exhaust fluid. These pipes are all preferably covered with insulating material, not shown. For controlling the temperature within the car, the inlet to each radiator is preferably provided with an automatic valve 27, controlled by a thermostat within the car. Any suitable well-known form of thermostatically controlled valve may be employed, al-

though I preferably use a type of valve in which compressed air, controlled by a thermostat, acts upon a diaphragm connected to the radiator valve. I may supply the necessary compressed air from the air brake pipe line, through a pressure reducing valve.

Instead of using the specific form of radiator shown in Figs. 1 to 4 inclusive, and heating the same by steam, I may make various changes in the construction and operation.

By means of the constructions above described, I am able to keep the interior of the car at any desired temperature, so long as an adequate supply of heating medium is delivered through the pipe line 24. This is easily accomplished, when the car is coupled to the locomotive, but such coupling is not possible in many localities at the time when the car is being loaded. As previously stated, such fruits as bananas and pineapples arrive in this country almost entirely by ship, and the common method of handling these fruits as well as other freight at many seaports, such for instance as New York, necessitates the transporting of the cars to and from the ship side on car floats.

My invention permits maintaining the car in proper heating condition, while being transported to and from the ship side, and while being loaded. The cars are commonly moved from the railroad terminal to the ship side on car floats which may have suitable couplings for connecting them to the steam pipes on the cars so that when an order is received for the unloading of the cargo from a ship, the car float may take on its load of empty cold freight cars and proceed to the ship. In the meantime, the radiators may be raised to operative position, the false flooring lowered and the steam turned on, also the lining paper and hay may be put in place if such be employed. By the time the barge reaches the ship side, the cars will be adequately heated to permit the immediate transfer of the fruit thereto. Instead of supplying heat from the heating plant on the float, steam may be taken from the boiler of the tug conveying the float, or steam from the tug boiler may be delivered to the boiler of the float plant, to hurry the heating of the latter if it be cold when called into use. The heating plant 31 may be heated with oil fuel which may be stored on the float or on the pier. A steam pipe line may be run along the pier if desired.

By means of my invention, not only is great saving of time effected, but there is also a great reduction of the liability of freezing the fruit, and the heating of the cars is rendered much safer than is the case where the old method is employed which involves the placing of a series of oil stoves in each car to warm it before the fruit is load-

ed, and a stopping of the train at different points along the line to reheat the cars by oil stoves, if the weather be particularly cold, or if the trip be a long one. I also reduce the number of men which need be employed at the terminal and a smaller train crew can properly take care of the cargo.

The cars may be used for handling the ordinary freight as the features involving my invention do not in any way interfere with the general use of the car. When it is desired to transport goods to be heated, the parts involved in the heating system may be brought into operation in a very few minutes and without requiring any skilled labor.

Having thus described my invention, what I claim as new and desire to protect by Letters Patent is,

1. A freight car having a recess in the floor thereof, a closure for said recess, a radiator, a supply conduit, and connections between said conduit and said radiator, and permitting the latter to be raised out of said recess and supported above said floor upon the removal of said closure. 90

2. A freight car having a recess in the floor thereof, a radiator normally disposed within said recess, a closure for said recess, a supply conduit, connections between said conduit and said radiator, and permitting the latter to be raised out of said recess and supported above said floor upon the removal of said closure, and a removable false flooring adapted to be supported above said radiator, when the latter is in its raised position. 100

3. In combination, a radiator, links pivoted thereto adjacent to opposite ends, and permitting said radiator to be raised or lowered with respect to its support, and a false flooring supported above said radiator 105 when the latter is in raised position, and having openings therethrough for the circulation of air.

4. A freight car having a chamber, a substantially flat radiator normally disposed 110 closely adjacent to the floor of said chamber, means for supporting said radiator in a raised or lowered position, and perforated false flooring removably supported above said radiator when the latter is in raised 115 position.

5. A freight car having a recess in one wall thereof, a radiator movable into or out of said recess, a closure for said recess when said radiator is disposed within the latter, 120 and a removable wall adapted to cover said radiator when the latter is moved out of said recess.

6. A freight car having a recess in the floor thereof, a radiator movable to a position within said recess and below the inner surface of said wall, a closure for said recess, serving to conceal said radiator, supports for holding said radiator in raised position out of said recess, and a false flooring adapted to 130

be supported above said radiator when the latter is in a raised position, and permitting a free circulation of air between the main body of said car and the space between the 5 car floor and said false flooring.

7. In combination a freight car, a radiator therein, means for supporting said radiator closely adjacent to or spaced from one wall of said car, a supply conduit beneath the car 10 floor and connected with said radiator, a substantially imperforate cover for said radiator when the latter is in the first mentioned position, and a perforated cover for said radiator when the latter is in said second-mentioned position.

8. In combination, a chamber having a recess in the floor thereof, a radiator, a supply conduit, connections between said conduit and said radiator and permitting a raising and lowering of said radiator out of or 20 into said recess, means for supporting said radiator in raised position, and a removable false flooring adapted to be supported above said radiator when the latter is in its 25 raised position.

9. A freight car having a wall provided with a recess therein extending lengthwise thereof, a radiator formed of a plurality of pipes connected together in series and extending lengthwise of said recess, a supply 30 conduit, an exhaust conduit, connections between said conduits and said radiator whereby the latter may be swung into or out of said recess and means for supporting 35 the radiator when out of said recess.

10. A freight car having a main flooring provided with a recess therein extending lengthwise thereof, a radiator formed of a plurality of pipes connected together in 40 series and extending lengthwise of said recess, a supply conduit, an exhaust conduit, connections between said conduits and said radiator whereby the latter may be swung upwardly, means for supporting said radiator in raised position, and a removable false 45 flooring disposed above said radiator when the latter is in raised position.

11. A freight car having a recess in one wall thereof, a closure for said recess, a 50 radiator, a supply conduit and connections

between said conduit and said radiator and permitting the latter to be moved out of said recess and supported within the chamber of the car upon the removal of said closure.

12. A freight car having one wall thereof 55 provided with a recess therein extending lengthwise of the car, a radiator formed of a plurality of pipes connected together in series and extending lengthwise of said recess, a supply conduit, an exhaust conduit, 60 connections between said conduits and said radiator whereby the latter may be swung out of or into said recess, and means for preventing goods within the body of the car from coming in contact with said radiator 65 when the latter is moved out of said recess.

13. A freight car having supply and exhaust conduits extending through the floor thereof, a radiator within the car and connected to said supply and exhaust conduits, 70 said radiator being normally disposed below the level of the upper surface of the floor and movable substantially vertically with respect to said floor and said conduits, whereby it may occupy a position spaced 75 above said floor, and means for preventing goods within said car from coming in contact with said radiator when the latter is in said raised position.

14. A freight car having a steam supply 80 pipe extending lengthwise thereof and beneath the floor, a pair of recesses in the upper surface of the floor and extending lengthwise of the car upon opposite sides of the center line, a radiator at each recess, 85 each of said radiators being formed of a plurality of pipes connected together in series and extending lengthwise of the adjacent recess, and separate connections extending from said radiators to said supply pipe and 90 permitting the raising and lowering of said radiators.

Signed at New York, in the county of New York and State of New York, this 10th day of July, A. D. 1914.

ALFRED LEE MOORSHEAD.
